Atty.

UNITED STATES PATENT OFFICE

STANLEY F. RAGAN, OF CHICAGO, ILLINOIS

WINDOW LOCK

Application filed May 18, 1931. Serial No. 538,127.

The present invention relates to window locks which has for its main object the provision of a lock which may limit the relative movement of upper and lower window sashes.

5 A further object of the invention is the provision of a window lock which may consist of two hingedly connected plates, and which may be simple in construction and operation.

10 A further object of the present invention is the provision of a window lock, which, in addition to the facility of limiting movement of the upper and lower sashes, may at the same time serve as an anti-rattling device.

15 With the above general objects in view and others that will appear as the nature of the invention is better understood, the same consists in the novel construction, combination and arrangement of parts hereinafter 20 more fully described, illustrated in the accompanying drawing and pointed out in the appended claims.

In the drawing forming a part of this application and in which like designating characters refer to corresponding parts throughout the several views,

25 Figure 1 is an elevational view of two window sashes with the lock shown in an operative position;

30 Figure 2 is a cross-sectional view on line 2—2 of Figure 1;

Figure 3 is a cross-sectional view on line 3—3 of Figure 1;

35 Figure 4 is an elevational perspective view of the window lock while the same remains in an open inoperative position; and

Figure 5 is a cross-sectional view through the window lock on line 5—5 of Figure 3.

40 Referring in detail to the present drawing there is shown therein the usual window frame 10, with the upper and lower sashes therewithin for upright sliding movement. The lower sash includes the usual horizontal bar 11 and one of the upright bars 12. The upper sash includes the lower horizontal sash bar 13 and one of the upright bars 14. The two sashes are spaced on horizontal plane with spacing strip 15, projecting from the window frame 10, interposed therebetween. Usual window pane in the lower sash is in-

dicated by 16, and a window pane in the upper sash is indicated by 17. Adapted for mounting by screws 18, passing through suitable apertures, is a substantially rectangular plate 19. Formed at the horizontal edges thereof are outwardly extending flanges 20, for the purpose hereinafter described. Near its one vertical edge and substantially at the central portion thereof said plate 19 is provided with a substantially square opening 21, which at one of its sides is defined by an outwardly projecting strip 22, for the purpose which will be later apparent.

The window lock proper cooperating with plate 19 is also formed out of a single metal sheet suitably formed to include a central loop or ridge 23 horizontally disposed while the window lock remains in an operative position in a window, said ridge 23 forming a stop 45 for the upright relative sliding movement of the two sashes. Extending from said ridge 23 on both sides is a pair of tapered plates 24, each of which at one of its corners having 50 lugs 25 formed therein, for insertion within 55 a corresponding aperture formed at one end of each flange 20 for the purpose of forming a hinge connection with plate 19.

For the purpose of interlocking the two hingedly connected portions of the lock, or 60 in other words, to bring about the operative or inoperative position of the lock, a suitable latching device is provided between said two portions. Said latching device includes a substantially rectangular body portion 26 insertable within the outer free ends of the 65 said walls of ridge 23. Said rectangular portion of the latching device is provided with lateral depressions 27. The side walls of 70 said ridge 23 are clinched with the resultant 75 inner bulges 28 on the inner faces of sides of ridge 23, which are adapted to enter depressions 27, by means of which said body portion 26 remains in pivotal arrangement 80 within said ridge 23.

Said body portion 26 is provided with lug 85 90 95 99 which is co-extensive with ridge 23. Interposed between said lug 29 and apex of ridge 23 is a coil spring 30 for normally urging said lug away from said ridge 23. One 100

of the ends of said coil spring 30 is in rigid engagement with lug 29 for the purpose of preventing displacement of said coil spring. Rigidly formed with said body portion 26, and extending from one end of said body portion 26, and in an angular portion with respect to said lug 29 is hook 31 which remains in a transverse relation with ridge 23, which is adapted to enter opening 21 to engage the outwardly bulging strip 22, as clearly seen on Figure 3.

One end of the body portion 26 of the latching device aforesaid, extends beyond the outer end of ridge 23 and the side walls thereof, and has knob 32 rigidly formed therewith, which knob projects outwardly and beyond ridge 23. From the hereinabove description it will be seen that depressions 27 in the body portion 26, with the cooperating inward bulges 28 entering said depressions form a fulcrum for said body portion 26 of the latching device so that by manual angular shifting of knob 32 away from the adjacent end of ridge 23 and its side walls hook 31 may be disengaged from bulging strip 22 in the plate 19, whereby the two hingedly connected portions of the lock may be shifted to an inoperative position shown on Figure 4. When said two cooperating parts of the locking device are closed, hook 31 will enter opening 21 and will automatically spring into an engaging position with strip 22 by virtue of the pressure and action of spring 30 at lock 29. When in an operative position shown on Figs. 1, 2 and 3, ridge 23 and its side walls will form a stop for the horizontal upper sash bar of the lower window sash preventing the relative upright shifting movement of the upper and lower sashes, as seen on Fig. 2. When the two hingedly connected portions of the lock are disengaged by angularly shifting knob 22 for disengaging hook 31 from strip 32, the movable part of the locking device may be brought to the position shown on Fig. 4, whereby the lock will remain in an inoperative position and away from the path of movement of the upper horizontal bar of the lower window sash, as indicated by dotted lines on Fig. 3. In that latter position ridge 23 will face the window pane 17 of the upper window sash, as shown by dotted lines on Fig. 3.

To facilitate manual withdrawal of the outer shifting movement of lock on withdrawal of hook 31 from engagement thereof with strip 22 on manually angularly shifting of knob 32, inwardly disposed bulges 33 are provided at substantially central portions of side walls of ridge 23, which bulges facilitate the manual grasp of the ridge for the purpose of manual withdrawal of the hinged movable part of the lock from plate 19.

The object of making plates 24 tapered or

at least the bottom one, is to provide a stopping means for holding the upper and lower window sashes in frictional engagement so as to prevent the relative side movements of said sashes and thereby to prevent their rattling. The horizontal upper sash bar of the lower window sash on being raised will frictionally engage the adjacent face of the tapered plate 23, as seen on Figure 2, in consequence whereof the two sashes will be caused to remain in rigid relative adjustment. Thus, the relative movement and consequent rattling will be prevented.

Flanges 20 prevent any displacement of the shiftable portion of the lock in relation with plate 19. Any attempt of breaking the lock by forcible shifting of a window sash against a lock will be prevented due to the fact that flanges 20 prevent relative displacement of the shiftable portion of the lock relative to its position with plate 19, as is apparent from Figure 2.

While there is described herein a preferred embodiment of the present invention, it is nevertheless to be understood that minor changes may be made therein, without departing from the spirit and scope of the invention as claimed.

What I claim as new is:

1. A window lock comprising a plate, another plate hingedly connected to said first mentioned plate, a projection upon said last mentioned plate angularly disposed with relation thereto, said first named plate having an opening made therein, defining a strip at one edge of said first named plate, and a hook at said second named plate and in a shifting relation therewith, said hook being adapted to enter said opening for engaging said strip for the purpose of interlocking the two plates.

2. A window lock comprising a plate adapted for mounting upon the window sash, said plate having an opening defining a strip at one edge of said plate, a U-shaped ridge, a wing plate laterally extending from each side of said ridge, said wing plates being provided with means for hingedly engaging said first named plate, whereby said ridge and said wing plates are adapted for angular shifting movement with respect to said first named plate, and a latching device mounted within said ridge adapted to engage said strip in said first named plate for the purpose of interlocking said ridge and said wing plates with said first named plate.

3. A window lock comprising a plate adapted for mounting upon the window sash, said plate having an opening defining a strip at one edge of said plate, a U-shaped ridge, a wing plate laterally extending from each side of said ridge, said wing plates being provided with means for hingedly engaging said first named plate, whereby said ridge and said wing plates are adapted for angular shifting

movement with respect to said first named plate, a latching device mounted within said ridge, adapted to engage said strip in said first named plate for the purpose of interlocking said ridge and said wing plates with said first named plate, and flanges at the edges of said first named plate and angularly disposed with relation thereto, outer edges of said wing plates being adapted to contact with said flanges for the purpose of preventing shifting thereof on a plane co-extensive with the plane of said first named plate.

4. A window lock comprising a plate for mounting upon the window sash, a U-shaped ridge, wing plates extending laterally from said ridge, a hinge connection between said plate and said wing plates permitting said wing plates and said ridge to make angular shifting movements with respect to said first named plate for closing or opening said ridge and said wing plates with respect to said first named plate, and means for interlocking said first named plate with said ridge when the latter is angularly shifted to a closed position with respect to said first named plate.

5. In a window lock including a plate and a U-shaped member hingedly connected therewith, the combination of a latching device comprising a body portion impinged within said U-shaped member for pivotal movement therewithin, a hook integrally formed with said body portion, and means upon said plate whereat said hook is adapted to engage for interlocking said plate with said U-shaped member when the same are in an operative position.

6. In a window lock including a plate and a U-shaped member hingedly connected therewith, the combination of a latching device comprising a body portion impinged within said U-shaped member for pivotal movement therewithin, a hook integrally formed with said body portion, tensioning means interposed between said body portion and the apex of said U-shaped member for normally urging said body portion toward said plate when said U-shaped member is in an operative position with respect to said plate, and means upon said plate whereat said hook is adapted to engage for interlocking said plate with said U-shaped member when the same are in an operative position.

7. In a window lock including a plate and a U-shaped member hingedly connected therewith, the combination of a latching device comprising a body portion impinged within said U-shaped member for pivotal movement therewithin, a hook integrally formed with said body portion, tensioning means interposed between said body portion and the apex of said U-shaped member for normally urging said body portion toward said plate when said U-shaped member is in an operative position with respect to said plate, means upon said plate whereat said hook is adapted

to engage for interlocking said plate with said U-shaped member when the same are in an operative position, and means for manually shifting said body portion against the pressure of said tensioning means for disengaging said hook from said second named means.

In testimony whereof I affix my signature.
STANLEY F. RAGAN.
